(57) **CLAIM**

The ornamental design of a storage device, substantially as shown and described.

DESCRIPTION

FIG. 1 is a perspective view of a storage device in accordance with the present design;

FIG. 2 is a front elevation view thereof;

FIG. 3 is a back elevation view thereof;

FIG. 4 is a first-side elevation view thereof;

FIG. 5 is a second-side elevation view thereof;

FIG. 6 is a top view thereof; and,

FIG. 7 is a bottom view thereof.

The broken lines in the Figures show environmental structure of the storage device which form no part of the claimed design.

1 Claim, 7 Drawing Sheets
